UNITED STATES PATENT OFFICE

ROSSWELL W. THOMAS, OF BARTLESVILLE, OKLAHOMA, ASSIGNOR TO PHILLIPS PETROLEUM COMPANY, OF BARTLESVILLE, OKLAHOMA, A CORPORATION

LIQUID GAS CONTAINER

Application filed October 8, 1929. Serial No. 398,239.

This invention relates to improvements in containers particularly well adapted for use in the handling and distribution of liquefied petroleum gas, or the like, to consumers.

5 The Philfuels Company, of Bartlesville, Oklahoma, a subsidiary of the Phillips Petroleum Company, have made the utilization of gas available to consumers remotely located from city gas mains, by a system of 10 distributing liquefied petroleum gas to the consumer, which liquefied gas is highly volatile, and the vapor of which is used as fuel by the consumer. A consumer's service installation requires a container for the liquefied gas, which must be economically produced for efficiently receiving the liquefied gas against liability of leakage. The container must have liquid inlet and vapor outlet connections, and means is provided for 15 weighing the container and the liquefied gas therein, in order to gauge the consumption; these features being more particularly set forth in the co-pending application, Serial 20 No. 280,746, filed May 26, 1928.

25 In the present invention a metallic container of cylindrical form is provided, having improved connections in the top thereof for receiving inlet and outlet valves and a siphon tube, and provided with an improved connection axially thereof for supporting the container in a well balanced relation upon scales, for weighing purposes.

30 Other objects and advantages of this invention will be apparent during the course 35 of the following detailed description.

In the drawing, wherein for the purpose of illustration is shown only a preferred embodiment of the invention,

40 Figure 1 is a side elevation of the improved drum or container.

Figure 2 is a top plan view of the container.

Figure 3 is a vertical sectional view taken through the container substantially on the line 3—3 of Figure 2.

45 Figure 4 is a fragmentary sectional view of the top portion of the container.

Figure 5 is a fragmentary sectional view of a valve and tube connection for the container.

50 In the drawing, wherein similar reference

characters designate corresponding parts throughout the several views, the letter A may generally designate the container, which is of metal, including a cylindrical shaped body 10 and an integral dome-shaped top 55 wall 11. The cylindrical body 10 is fabricated by the ordinary drawing process. The cylindrical body 10 is of uniform diameter from end to end, and in the lower end thereof is disposed a separate dome-shaped bottom wall 12, which fits entirely within the lower portion of the cylindrical body 10, bulging convexly downward but terminating at its apex short of the bottom edge 13 of the skirt portion 14 at the lower end of 60 the cylindrical body 10. The dome-shaped separate bottom wall 12 is provided with an upstanding annular attaching flange 15 which may be secured in any manner, as by welding shown at 17 in the drawing, to the 65 inner peripheral portion of the body 10, for connecting the bottom 12 in a leak-proof relation in the bottom of the cylindrical body 10. The container A stands upon its lower edge, upon a suitable foundation, which the 70 bottom 12 does not contact.

The top wall 11 of the seamless steel portion of the container bulges convexly upwardly, and axially of the container, centrally on the top wall 11, there is provided a 80 preferably polygonal nut 20, which is electric welded as at 21, but may be otherwise attached. It has a screw threaded socket 22 facing upwardly for detachable connection of a hook-shaped member 25, which receives 85 the bail or suitable connecting link of weighing mechanism, by means of which the container, together with its liquid contents may be weighed for gauging purposes, as more particularly set forth in the co-pending application above mentioned. The nut 20, together with the detachable hook 25 is not only economical, but enables a facile weighing operation to take place.

90 Eccentrically in the top wall 11 of the container there are provided inlet and outlet connecting vents 30 and 31 respectively, preferably both adjacent the same side of the container, and not diametrically opposed with respect to the connection 25. The con- 95 100

nections 30 and 31 are of sleeve-like formation, the same being relatively long and inserted through openings which are drilled in the top wall 11, so that the major lengths of the 5 said sleeve portions are disposed downwardly from the inner side of the wall 11, as shown in Figure 4, with relatively small extensions exteriorly of the wall 11. These sleeves 30 and 31 have screw threaded passageways 33 therethrough, wherein the screw threaded 10 shanks of valves or the like may be disposed. The connection 31 receives an exterior valve thereon (not shown) for release of the gaseous vapor from the top of the tank. The 15 sleeves 30 and 31 are electrically welded at 37, in place upon the wall 11, in the relation mentioned, so that they are axially parallel with the axis of the tank. The connection 30 receives a high pressure valve 50, which has 20 an elongate screw threaded shank 51 detachably threaded into the screw threaded passageway 33. The passageway 53 of the shank 51 of the valve 50 is provided with a 25 downwardly facing screw threaded socket 54 therein, adapted to detachably receive the upper screw threaded end 55 of a siphon tube or pipe 40, as shown in Figures 3 and 5 of the drawing. The relation of the valve and siphon tubes 40 permits of the disconnection 30 of both from the sleeve or nipple 30 simply by unscrewing the valve, and withdrawing the tubes. The tube 40 extends down within the container compartment, to within about one-half inch of the bottom 35 wall 12.

In the filling of the container, the liquefied gas is entered through the connection 30 and passes downwardly through the tube 40 for filling the tank. The gaseous vapor enters 40 the customer's service line through the connection 31. The tube 40 enables a ready siphoning of the liquefied contents of the container, should it become necessary to empty the container. 45 Various changes in the shape, size, and arrangement of parts may be made to the form of invention herein shown and described, without departing from the spirit of the invention or the scope of the claims. 50 I claim:

1. In a drawn metal container, a cylindrical body having a dome-shaped top wall, said top wall provided with an opening, the axis thereof parallel to the axis of the cylindrical body and to one side of the crown portion of the top wall, and an elongate internally screw threaded sleeve fitting and extending through said opening, welded at its upper portion to the curved outer surface of 55 the top wall.

2. In a drawn metal container, a cylindrical body having a dome-shaped top wall, said top wall provided with an opening, the axis thereof parallel to the axis of the cylindrical body and to one side of the crown 60

portion of the top wall, an elongate sleeve fitting and extending through said opening with the greater portion of said sleeve within said container, said sleeve welded at its upper portion to the curved outer surface of 70 the top wall and provided with a screw threaded bore, and connection means including an elongate shank provided with screw threads and detachably secured by said screw threads to said sleeve. 75

3. A closed drawn steel container having a convex surface, and a relatively small mass of metal welded on the surface preserving the convexity of the surface at that point, said mass of metal having a recess or hole 80 therein, said recess or hole having such shape as to adapt it to receive a hook-like element, the longitudinal axis of the hook-like element passing through the center of gravity 85 of the container.

4. A closed drawn steel container having a dome-shaped upper portion, and a relatively small mass of metal welded on the apex portion of said dome-shaped portion without deformation of said portion, said mass of 90 metal having a recess or hole therein, said recess or hole having such shape as to adapt it to receive a hook-like element, the longitudinal axis of the hook-like element passing through the center of gravity of the container. 95
